UNITED STATES PATENT OFFICE

105,973

DESIGN FOR A CAMERA

Walter D. Teague, New York, N. Y., assignor to
Eastman Kodak Company, Rochester, N. Y.,
a corporation of New Jersey

Application July 23, 1937, Serial No. 70,601

Term of patent 7 years

To all whom it may concern:

Be it known that I, Walter D. Teague, a citizen of the United States of America, residing at New York city, in the county of New York and State of New York, have invented a new, original, and ornamental Design for a Camera, of which the following is a specification, reference being had to the accompanying drawings, forming a part thereof, in which:

Fig. 1 is a perspective view of a camera showing my new design, the camera being in an open or picture-taking position.

Fig. 2 is a top plan view of the camera shown in Fig. 1 but with the camera in a folded position.

Fig. 3 is a front elevation of the camera shown in the preceding figures with the camera in a folded position, and

Fig. 4 is a rear elevation of the camera shown in the other views.

I claim:

The ornamental design for a camera as shown and described.

WALTER D. TEAGUE.
